CLAIM

The ornamental design for a garment, as shown and described.

DESCRIPTION

FIG. 1 is a front view of a garment according to a first embodiment of the design;

FIG. 2 is a rear view thereof;

FIG. 3 is a right side view thereof;

FIG. 4 is a left side view thereof;

FIG. 5 is a front perspective view thereof;

FIG. 6 is a rear perspective view thereof;

FIG. 7 is a front view thereof shown in an environment of use;

FIG. 8 is a front view of a garment according to a second embodiment of the design;

FIG. 9 is a rear view thereof;

FIG. 10 is a right side view thereof;

FIG. 11 is a left side view thereof;

FIG. 12 is a front perspective view thereof;

FIG. 13 is a rear perspective view thereof; and,

FIG. 14 is a front view thereof shown in an environment of use.

The portions of the garment shown in broken lines in FIGS. 1-2, 5-9, and 12-14 form no part of the claimed design. The broken line showing of the legs, arms, and torso in FIGS. 7 and 14 is for the purpose of illustrating portions of the environmental structure and forms no part of the claimed design.
